UNITED STATES PATENT OFFICE.

ORRIE W. NEAL, BURTON W. SHAW, AND HARRY J. HOWARTH, OF PORTLAND, MAINE.

SEAL FOR ELECTRIC WIRES.

No. 905,349.

Specification of Letters Patent.

Patented Dec. 1, 1908.

Application filed August 15, 1908. Serial No. 448,709.

To all whom it may concern:

Be it known that we, ORRIE W. NEAL, BURTON W. SHAW, and HARRY J. HOWARTH, citizens of the United States of America, and residents of Portland, county of Cumberland, State of Maine, have invented certain new and useful Improvements in Seals for Electric Wires, of which the following is a specification.

10 Our invention relates to a seal for sealing and insulating the bare end of insulated electric wires such as are used for carrying light and power current into houses and other buildings.

15 In conducting the business of supplying light and power to buildings the heavily insulated wires are carried through the walls of the building to a point where they are to be connected to the fuse or switch. The 20 insulation is then removed from the ends of the wires and connection is made by means of these bare ends. When the meter is taken out or the service discontinued connection may easily be made by inserting 25 fuses and connecting the wires where the meter was inserted and current taken without the knowledge of the company. There is also considerable danger in leaving live 30 wire terminals in a building exposed to careless handling and numerous accidents have happened both to persons and property on this account.

The object of our invention is to provide a simple and inexpensive means of protecting 35 and sealing the bare ends of insulated wire terminals to prevent unauthorized use of current and danger from short circuiting.

The invention consists of an insulating casing made of two parts which are adapted 40 to fit together to embrace the insulated portion of the wire and to form a space to inclose the bare end with a sealing device for sealing and fastening the two parts of the casing together.

45 In connection with our wire seal, we make use of a tag for the purpose of keeping a record of the unused services. As here shown the tag *d* with a coupon attached is secured to the casing by passing the sealing 50 rivet through a hole in the tag before the rivet is sealed thus fastening the tag against the face of the casing. The tag is provided with a printed form showing the necessary entries to be made.

55 When the seal is to be removed the head of

the rivet may be cut off with a knife or removed in some other suitable manner.

A sealing device made as above may be cheaply manufactured and easily applied and will prevent the stealing of current and 60 the danger which comes from exposed live wires.

The two parts of the casing may be sealed otherwise than by the sealing rivet herein described the form of the sealing device being immaterial so long as the parts cannot be separated without breaking the seal.

We illustrate our invention by a form of sealing device which we have found well adapted to the purpose although other forms 70 may be used.

In the drawing, Figure 1 is a view of one of the hollow shells constituting one of the halves of the casing showing the wire in place, Fig. 2 is a transverse section through 75 Fig. 1 and Fig. 3 is an elevation of the seal with a recording tag fastened in place.

Referring to the drawing, *B* is the insulated portion of the wire which insulation is removed for some distance back from the 80 end leaving the bare wire *b*.

The seal is made up as here shown of the two part casing made of suitable insulating material such as porcelain.

The casing is made of two similar halves 85 or shells *A* adapted to fit together and as here shown, each is recessed to form when together, a cylindrical recess adapted to closely embrace the insulated portion of the wire with an enlarged shallow recess *a'* of 90 suitable size and formed to receive and contain the end of the wire *b* which is in the form of a loop as it is taken from its regular connection.

The two halves of the casing *A* are secured together so that the casing cannot be separated without breaking the seal. As here shown I make use of a sealing rivet *c* made preferably of lead or other soft metal, this rivet passing transversely through the center of the recess *a'* and being protected from contact with the wire by a hub or boss *a* which projects inward from each shell. The sealing rivet is upset at *c* after the casing has been applied to the wire and a suitable impression made on the head.

We claim;—

1. The herein described seal for the ends of insulated electric wires consisting of an insulating casing in two parts adapted to 110

- embrace the insulated portion of the wire and to inclose the bare end and a seal for securing together the two parts of said casing.
- 5 2. The herein described seal for the ends of insulated electric wires, consisting of an insulated casing in two parts adapted to embrace the insulated portion of the wire and to inclose the bare end and a sealing rivet passing through said casing to secure the two parts together and insulated from said bare end.
- 10 3. The herein described seal for the ends of insulated electric wires consisting of a casing composed of two shells adapted to fit together and to embrace the insulated portion of the wire with an enlarged shallow recess to contain the bare end, a hub extending through said recess around which hub the bare end is bent and a sealing rivet pass-
- ing through said hub to seal and fasten the two parts together.
- 15 4. The herein described seal for the ends of insulated electric wire consisting of a hollow casing in two parts adapted to embrace the insulation of the wire and to form a recess to receive the bare end, a sealing rivet passing through the two parts of said casing to seal and fasten them together and a tag through which the rivet passes and which is held against the casing by the head of said rivet.
- 20 In witness whereof, we have hereunto set our hands this 12th day of August, 1908.
- ORRIE W. NEAL.
BURTON W. SHAW.
HARRY J. HOWARTH.
